(57) **CLAIM**

The ornamental design for a spill tray for a home brewing machine, as shown and described.

DESCRIPTION

FIG. 1 is a perspective view of a spill tray for a home brewing machine with tapered spill grooves that filter down the drain hole in the middle of the tray showing my new design;

FIG. 2 is a top view of the spill tray illustrating the features of the tapered spill grooves that filter down to the drain hole illustrated in the middle of the tray;

FIG. 3 is a bottom view of the spill tray illustrating a completely flat bottom, further illustrating a drain hole in the center of the spill tray;

FIG. 4 is a back side view of the elevated spill tray illustrating the side tangent points of the radius features of the design;

FIG. 5 is a front side view of the elevated spill tray illustrating the side tangent points of the radius features of the design that fits flush against the front of the home brewing machine;

FIG. 6 is a right back side view of the elevated spill tray illustrating the side tangent points of the radius features of the design; and,

FIG. 7 is a left back side view of the elevated spill tray illustrating the side tangent points of the radius features of the design.
